UNITED STATES PATENT OFFICE.

CLARENCE H. ELLINGWOOD, OF BARSTOW, CALIFORNIA.

RAILROAD-YARD.

1,258,757.

Specification of Letters Patent. Patented Mar. 12, 1918.

Application filed September 7, 1917. Serial No. 190,197.

To all whom it may concern:

Be it known that I, CLARENCE H. ELLINGWOOD, a citizen of the United States of America, residing at Barstow, in the county 5 of San Bernardino and State of California, have invented certain new and useful Improvements in Railroad-Yards; and I do hereby declare the following to be a full, clear, and exact description of the invention, such as will enable others skilled in the 10 art to which it appertains to make and use the same.

This invention relates to railway yards and is particularly directed to a new and improved lay-out for railway yards whereby cars may be readily taken from a receiving yard in which they are placed after they have completed a run, and moved to a classification yard in which trains are made 15 up for succeeding runs. It is a primary object and purpose of my present invention to so construct and lay out the yard that the making up of trains may be greatly facilitated with the substantial elimination of 20 switch engines which are now used to move the cars from the receiving to the classification yards, there being utilized instead, a car-moving motor car which runs on separate and distinct tracks from those on which 25 the railway cars are carried.

For an understanding of the invention reference may be had to the accompanying drawing in which the figure shows, diagrammatically, the lay-out of a yard constructed in accordance with my invention. 30

The rails of the main track are indicated at 1 from which other track rails 2 and 3 branch at a distance from each other, extending outwardly at an angle as indicated 35 in the drawing to any desired distance dependent upon the size of the yard. From the tracks 2, other tracks 4 extend substantially parallel to the main tracks 1, while at their ends tracks 2 terminate in branches 40 5 also parallel to the tracks 1 and 4 as shown. On tracks 4 and 5 the cars are placed after completion of a run, said tracks comprising the receiving yard for the cars. Likewise from the tracks 3 tracks 6 branch, 45 being disposed in parallel relation to the main tracks 1, said tracks 3 terminating, likewise, in tracks 7 which parallel the tracks 6 and 1 as shown. The cars are moved from the receiving yard to these 50 55 tracks, which comprise the classification yard, in making up trains for later runs.

Alongside track 1, an auxiliary track is laid comprising spaced apart rails as indicated at 8 which parallel the track 1 as shown, from which auxiliary track branch 60 tracks are extended, as indicated at 9 and 10, parallel to the tracks 2 and 3, respectively. From the tracks 9 branch tracks 11 extend, lying between and paralleling the tracks 4 and being positioned alternatingly 65 between said tracks so that the receiving yard includes for each pair of tracks 4 a branch track the rails 11 of which are disposed between the pairs of tracks 4. Similarly, from the tracks 10 other tracks 12 extend in the classification yard between pairs 70 of tracks 6.

The cars used in train service are run on tracks 1, 2, 3, 4, 5, 6, and 7, while on the auxiliary tracks 8, 9, 10, 11, and 12, a motor 75 car indicated at 13 is adapted to run, it preferably being equipped with a beam or stake 14 which may be turned in a horizontal plane at various angles to the motor car 13 adapting the end of the same to engage 80 with a car, as 15, on either of the tracks 4 to each side of the auxiliary motor track. The motor car may be driven in any suitable manner but, preferably, it will be electrically driven. With it the railway cars 85 may be readily moved from the receiving yard to the classification yard without the necessity of switch engines as heretofore. The usual signal and switch tower, indicated at 16, will be used in throwing the various 90 switches, and from which the driver of the motor car may be informed by signals, visible from a signal board indicated at 17, as to which cars he shall take from the receiving yard and move over to the classification 95 yard.

From the foregoing it will be apparent that I have devised a novel yard for sorting and classifying cars and one by means of which the cars may be readily moved 100 from the receiving to the classification sections of the yard. With this type of yard, by reason of the fact that the motor car is carried on a different track than the cars moved by it, it is possible to use one motor 105 car to shift the railway cars out of the receiving yard on to the main track, after which the same may be engaged by a second motor car and carried to the classification yard. Likewise, it is possible to always 110 move the railway cars ahead of the motor car and at any of the points where the rail-

way cars pass across the auxiliary motor tracks, so that the railway cars pass across and ahead of the motor car, it is necessary, merely, to give said railway car a strong 5 push or shove to carry it ahead under its own momentum for a distance, after which it may be again engaged by the motor car, it being merely necessary to swing the stake 10 over to the opposite side of the motor car. These features of operation make it possible to greatly accelerate the sorting 14 and classification of railway cars, at the same time effecting a great saving in labor, as will be apparent when it is remembered 15 that for handling a switch engine the services of five men in various capacities are required; while with the motor car the service 20 of a fireman and of a brakeman in both the receiving and classification yards, may be dispensed with.

I claim:

1. In a railroad yard, a main track, 25 branch tracks extending therefrom at a distance from each other, a plurality of branch tracks leading from said first branches extending oppositely from each other and substantially paralleling the main track, an auxiliary track likewise having branches 30 paralleling the main track and first mentioned branches thereof, and a plurality of

branches to said first branches of the auxiliary track paralleling the branches extended from the first mentioned branches of the main track and located alternately between the same, substantially as and for the 35 purpose described.

2. In a railroad yard, a main track, branch tracks extending therefrom at a distance from each other, a plurality of branch tracks leading from said first mentioned 40 branches, an auxiliary track paralleling the main track, branch tracks leading therefrom paralleling the first mentioned branches leading from the main track, and a plurality of branch tracks to said first mentioned 45 branches of the auxiliary track paralleling the branches leading from the first mentioned branches of the main track, substantially as and for the purpose set forth.

3. In a railroad yard, a main track, 50 branch tracks leading therefrom, and an auxiliary track likewise having branch tracks leading therefrom, said auxiliary track and branches thereof located adjacent and paralleling the main track and its 55 branch tracks, substantially as and for the purpose described.

In testimony whereof I affix my signature.

CLARENCE H. ELLINGWOOD.
